Lacey & Lacey, Attorney 5

UNITED STATES PATENT OFFICE.

FORD JOHNSON, OF HELENA, MONTANA.

STUB HOLDER FOR CHECK BOOKS.

Application filed August 31, 1926. Serial No. 132,787.

This invention relates to stub holders adapted to be applied to a check book and retain filled in stubs in a turned back position where they will be out of the way and prevented from interfering when filling in stubs of unused checks and also prevented from moving downwardly upon a newly filled in stub and causing it to be blotted before the ink has dried.

10 One object of the invention is to provide a stub holder which may be stamped from a strip of sheet metal and very cheaply produced.

Another object of the invention is to so 15 form the stub holder that it may be easily applied to a check book and not be liable to slip out of a position in which a portion of the holder is firmly gripped between the binding of the stubs.

20 Another object of the invention is to so form the holder that either a few or all of the stubs in a check book may be engaged and retained in a turned back position when the check book is open.

25 The invention is illustrated in the accompanying drawing, wherein

Figure 1 is a perspective view showing the stub holder applied to a check book;

Fig. 2 is a sectional view through the 30 check book and stub holder taken on the line 2—2 of Fig. 1;

Fig. 3 is an enlarged perspective view of the stub holder, and

Fig. 4 is a perspective view of a slightly 35 modified form of stub holder.

The stub holder constituting the subject-matter of this invention is formed from an elongated strip of sheet metal curved longitudinally to provide an arm or body portion

40 1 which is substantially of an ogee configuration so that, when the stub holder is in use, the arm may extend over a number of stubs 2 which have been previously filled in and retain them in a turned back position with

45 the front cover 3 of the check book opened. Before the strip of metal is bent to form the curved arm a tongue 4 is stamped from one end portion with its attached end spaced from the said end of the

50 strip and its free end extending toward the

opposite end of the strip. Either before or after the strip has been bent to assume the ogee configuration, it is bent transversely, preferably in alinement with the attached end of the tongue 4, in order to provide a 55 foot 5 which extends transversely from the arm in an opposite direction to the tongue. The foot and tongue are disposed in a common plane and preferably extend at right angles to the end of the arm from which they project. By comparing Figs. 3 and 4, it will be seen that the end portion of the strip from which the foot 5 is formed may be bent to dispose the foot either outwardly of the arm, as shown in Fig. 3, or beneath the arm, 60 as shown in Fig. 4, with the tongue extending in an opposite direction and disposed either beneath the arm, as shown in Fig. 3, or projecting outwardly therefrom, as shown in Fig. 4.

When the stub holder is in use, the check book is opened in the usual manner and the stubs which have been previously filled in are turned back, as shown in Fig. 1. The holder is then applied and if constructed as shown in Fig. 3 its foot 5 will rest upon the stub to be filled in when a check is written and its tongue 4 forced into the binding of the check book. In view of the fact that the tongue is narrow, it may be fitted between arms of 80 the metal staples 6 by means of which the stubs are secured together and the stub holder will be prevented from being turned and accidentally moved out of proper position to have its tongue gripped between the 85 bound end portions of the stubs. If the foot is bent to extend beneath the arm, the foot will be forced between the bound end portions of the stubs and the tongue will rest upon the stub to be filled in. In either case, 90 the holder will have a portion firmly gripped between the bound stubs and a portion resting upon a stub to be filled in and constituting a brace to prevent the arm from being moved by the pressure of the turned back 95 stubs out of position in which it will extend transversely across them. The free end of the foot is beveled, as shown at 7, so that it may be easily inserted between the bound stubs.

Having thus described the invention, I claim:

A stub holder for check books comprising an elongated strip of material curved longitudinally and having a longitudinally extending tongue cut from one end portion in spaced relation to the said end and facing

the opposite end thereof, the strip being bent transversely at the attached end of the tongue to form a foot extending from the strip in an opposite direction to the tongue and in a common plane therewith. 10

In testimony whereof I affix my signature.

FORD JOHNSON. [L. S.]
